UNITED STATES PATENT OFFICE.

WALTER S. RUSH, OF NEW YORK, N. Y.

SHIP'S-ORDER TRANSMITTING AND RECEIVING APPARATUS.

1,221,222.

Specification of Letters Patent.

Patented Apr. 3, 1917.

Application filed April 12, 1911. Serial No. 620,618.

To all whom it may concern:

Be it known that I, WALTER S. RUSH, a citizen of the United States, residing at New York city, in the county and State of New York, have invented certain new and useful Improvements in Ships'-Order Transmitting and Receiving Apparatus, of which the following is a specification.

My invention relates generally to signal-giving and receiving apparatus such as is employed aboard ship for the purpose of transmitting the pilot's or captain's orders to the engineer, for indicating the engineer's response to the orders given, and for indicating the actual engine movements whether they be in accord with the orders given or not.

The improvements which constitute my invention, while relating generally to a system of this kind, have particularly for their object to maintain under a desired degree of tension the wires that serve as the connections between the more or less widely separated signal-indicating and order-transmitting mechanisms and for automatically giving an alarm or other signal when any such wire is either broken or not under the desired tension; to indicate or give an alarm when the movement of the engine is not in accord with and in proper response to the order given; to automatically stop the engine should the movements thereof, as controlled by the engineer, be not in accord with and in proper response to the orders given to him; and to automatically operate by the movements of the engine itself the response parts of the order-transmitting apparatus, and other indicating apparatus, showing the operations of the engine. These and other objects of the invention are carried out and secured by means of apparatus in which are embodied my improvements and invention, and such apparatus is illustrated in the accompanying drawings and is hereinafter fully described.

Referring to the drawings—

Figure 1 is a view, diagrammatic in character, illustrating the several features of the invention in their combined and coöperating relations.

Fig. 2 is a face view of the pilot's instrument of a ship's telegraph, in which are embodied certain of the improvements of my invention, with parts broken away and other parts in section.

Fig. 3 is a central vertical section of the

apparatus shown in Fig. 2 taken on the line III—III of Fig. 2.

Fig. 4 is an edge view of the same apparatus.

Fig. 5 is a face view of the pilot's instrument shown in Fig. 2, indicating the positions assumed by the parts when one or both of the wires are broken.

Fig. 6 is also a face view indicating the positions assumed by the parts when one or both of the wires are too tight.

Fig. 7 is a longitudinal sectional view through a portion of the movable arm of the pilot's instrument drawn on an enlarged scale.

Fig. 8 is a sectional view of the handle of the pilot's instrument, taken on the line VIII—VIII of Fig. 3.

Fig. 9 is a face of the engineer's instrument of a ship's telegraph, embodying some of my improvements, parts of the casing being broken away and portions of the apparatus being represented in section.

Fig. 10 is a cross sectional view taken on the line X—X of Fig. 9.

Fig. 11 is a face view of the engineer's apparatus of a ship's telegraph, the inclosing casing being omitted, illustrating a different embodiment of the invention from that illustrated in Fig. 9, though the principles of operation are similar.

Fig. 12 is a sectional view taken on the line XII—XII of Fig. 11.

Fig. 13 is a detail view, in elevation, of the delay mechanism employed in automatically stopping the engine when it is run in a direction contrary to the order given.

Fig. 14 is a face view of mechanism embodying my improvements for automatically controlling from the movements of the engine, the response-indicating parts of the ship's telegraph, and other indicating apparatus, when employed, showing the movements of the engine.

Fig. 15 is an edge view of the apparatus illustrated in Fig. 14.

Fig. 16 is a central sectional view of the same apparatus, parts being in elevation.

Fig. 17 is a detail plan view of an indicator adapted to be automatically controlled by the apparatus shown in Figs. 14, 15 and 16.

Fig. 18 is a detail view illustrating the manner of connecting apparatus like that shown in Figs. 14, 15 and 16 with a turbine or gas engine.

Fig. 19 is an elevation or face view of the engineer's instrument of a ship's order-giving apparatus of the bell pull type embodying some of the features of my invention.

5 Fig. 20 is a sectional view of the apparatus shown in Fig. 19 taken on the line XX—XX of that view.

10 Fig. 21 is an elevation or face view of an engineer's apparatus similar in its general features to that indicated in Fig. 19, but illustrating certain modifications of the invention, and many of the parts of the apparatus being omitted for the sake of clearness.

15 Fig. 22 is a sectional view of the apparatus shown in Fig. 21, taken on the line XXII—XXII of that view.

Fig. 23 is a detail view in vertical section illustrating one of the bell pulls of the pilot's instrument.

20 Fig. 24 is a top plan view of the bell pull shown in Fig. 23.

Fig. 25 is a face view of the same.

25 Fig. 26 is a vertical sectional view of a bell pull of different construction from that illustrated in Fig. 23.

Fig. 27 is an elevation of the clutch device employed in connection with the bell pull apparatus illustrated in Figs. 19 to 22.

30 Fig. 28 is a view of the same clutch taken at right angles to Fig. 27, the clutching members being illustrated in section.

Fig. 29 is a horizontal sectional view on the line XXIX—XXIX of Fig. 27.

35 Referring to the drawings, and first particularly to Fig. 1, A indicates a marine engine, which may be of any approved type. For the purposes of illustration I have shown only a few of the well known parts of a reciprocating marine engine. Thus, a indicates part of the A-frame, b, the main throttle-controlling lever, c, the way-shaft, and d, the cross head. No attempt is made in the drawings to represent these parts in their exact locations, because as said, Fig. 1

40 is diagrammatic in character. E indicates the pilot's instrument of the ship's telegraph, and E', the pilot's bell pull apparatus, both of these and their associated engineer's instruments being shown because 45 similar arrangements are required by marine regulations, and because my invention is applied to both. F indicates the engineer's instrument of the ship's telegraph, and F', the engineer's signal apparatus connected with 50 the bell pull apparatus E'.

55 G indicates an alarm or signal adapted to automatically operate whenever the response of the engineer is contrary to the order received from the pilot. It is operatively connected with both the apparatus F and F'. H indicates apparatus for closing the main throttle valve whenever the response of the engineer is at variance with the order given by the pilot, it also being connected with 60 both apparatus F and F'. Combined with

and controlling the operation of the apparatus H is a delay mechanism, indicated by I. This mechanism is arranged to be set into motion whenever the response of the engineer is at variance with the order given 70 by the pilot, and is operated from some moving part of the engine, as for instance, from the cross head d, through connections i, and its function is to prevent the instantaneous stopping of the engine should it be turned in a direction contrary to that ordered, while insuring that the desired stoppage shall take place before the engine has moved far enough to do damage.

75 J designates a control mechanism connected with the way-shaft c, as by a chain or cord j. It is arranged to control or govern the indicators, as K, K', when they are used, and the response-indicating parts of the ship's telegraph. It is adapted to control 80 the indicators either through wires L, or through fluid pressure conductors M, or both these may be used. The latter are supplied with fluid under pressure from a suitable device operated by the engine, as for instance, from a pump N, connected through operative connections n, with a moving part of the engine, as for instance, with the cross head d.

85 The parts of the apparatus thus briefly referred to will in their details of construction, arrangement and their methods of operation, be more fully described herein-after, and are illustrated in the other views of the drawings.

90 100 Certain of the improvements comprised in my invention relate to means by which the wires connecting the pilot's and the engineer's instruments and through which signals are transmitted and received are kept under tension; and also by which an alarm, signal, or other indication is given whenever such wires break, or become too tight, or too loose, and I will now describe this part of the invention.

95 110 It is well known that a ship owing to varying load conditions and especially when in rough water at sea, is constantly bending or springing, with the result that the wires connecting the signal-giving and receiving 105 instruments, situated in widely separated parts of the vessel, are at one moment too slack and at another moment too tight for securing the best results. It is to overcome these defects and other adverse conditions 115 met with aboard ship that the improvements I am now to describe have been devised.

120 Referring particularly to Figs. 2 to 8, in which the pilot's ship's telegraph instrument E is illustrated, 2 designates the main dial 125 plate about which is moved the pointer 3 controlled by the handle 4 which the pilot grasps in transmitting signals to the engineer. The response pointer 5 is also movable in proximity to the dial plate and is 130

connected with the pulley 6 to which are secured the wires 10 through which the responses to the signals given are transmitted from the engine room. The wires 9 uniting the pilot's with the engineer's instrument and through which the orders from the former are transmitted to the latter, are connected respectively with pulleys 7 and 8 loosely mounted upon the shaft 11, on which 5 is also supported the wheel or pulley 6 already referred to. The wheels 7 and 8 are arranged side by side and preferably constitute a casing in which is situated a coiled spring 14, one end of which is connected 10 with the hub 12 of the wheel 7, and the other with the peripheral flange of the wheel or pulley 8. This spring when under tension operates to turn the wheels or pulleys 7 and 8 in opposite directions, and thus maintains 15 both wires 9 under proper stress, allowing them to pay out when the distance between the instruments E and F increases, or when the wires contact, and taking up the slack when they approach each other, or 20 when the wires stretch or are elongated. 25

Should one of the wires 9 break it manifestly becomes impossible to transmit signals to the engine room through that set of wires, and I have devised mechanism by 30 which the fact of such breakage is immediately indicated, and that mechanism I will now describe.

15 is an arm secured to one of the pulleys, as for instance, by being fastened to the hub 35 13 of the pulley 8. A link 16 connects the end of the arm 15 with a yoke 17 surrounding the movable radial arm 18 at the end of which is situated the handle 4. A link 19, of the same length as the link 16, and situated upon the side of the arm 18 opposite the link 16, unites the yoke 17 with the wheel 7, to which its outer end is pivotally connected. The yoke is free to slide upon the arm 18, but under normal conditions is held in the 40 position indicated in Fig. 2, by the tension of the wires, and is moved, along with the arm, whenever the latter is turned to give a signal. These movements of the arm and yoke operate through the links 16 and 19 to 45 turn the two wheels 7 and 8 in the same direction, letting off the wire from one of the wheels and winding it upon the other. Should a wire break, the wheel to which it is connected, under the influence of the spring 50 14, will rotate, being no longer restrained by the wire, and the end of the link, 16 or 19, connected with the pulley to which the broken wire is secured, will be carried, by the turning of the pulley, toward the arm 55 18. The result of this movement is to slide the yoke 17 outward along the arm 18, and as the angular relations of the two links, 19 and 16, with reference to the arm, must always be the same, the arm, which is free to 60 move, is turned until the parts come to rest 65

in the angular relations indicated in Fig. 5. In its outward movement along the arm 18, the yoke 17 engages with a stop 25 which finally arrests its movement, this stop preferably being in the form of a band encircling 70 the arm just below the handle 4, and supported so as to have a limited movement along the arm. It is illustrated as being supported by a pair of rods 26 26 which at their inner ends are loosely supported in 75 bearings in the hub of the arm 18. These rods are connected near their inner ends by cross-bar 28 and between this bar and the supporting bearings for the rods are springs 27 arranged to yieldingly hold them and the 80 stop band 25 in normal positions, as indicated in Figs. 2, 3 and 4, with the skirt of the hollow handle 4 covering the band 25, and concealing it from view.

The handle 4 is not rigidly connected with 85 the arm 18, but is united thereto by the link 21 and the rod 20, the latter being within the hollow arm 18 and surrounded by the spring 22. The spring when free to act tends to move the rod, and with it the link 90 21 and handle 4 outward, carrying the parts into the positions indicated in Fig. 5. It is, however, normally restrained and held under tension by a latch 23 that engages with the edge of an aperture in the arm 18 whenever the handle is forced down over the upper end of the arm into working position, as indicated in Figs. 2, 3 and 4. In order to trip the latch I employ a pair of toggle links 24 mounted in a slot formed in the 95 arm 18, and so disposed that when pressed inward from their normal positions, indicated in Figs. 3 and 7, they will engage with the latch. The yoke 17 when moved outward into the position shown in Fig. 5 operates to force the toggle links 24 inward and thereby trip the latch 23, releasing the spring 100 22. As soon as this occurs the rod 20 and link 21 are moved outwardly sufficiently far to carry the pivot that unites them beyond the end of the arm 18, which leaves the handle 4 free to tilt upon this pivot, as indicated by dotted lines in Fig. 5, so that if then grasped, the pilot will at once be advised that one or both of the wires have been 105 110 broken and the telepathy thereby rendered inoperative. Besides this method of indicating a broken wire, I also employ other means, as for instance, visual signals, two of which are indicated. One is a sign, bearing the words "Wire broken", and for this the band 25 is utilized, the sign being exposed when the handle is moved to uncover the band. Besides this, or in lieu thereof, I may employ flags 29 which will be exposed, 115 as indicated in Fig. 5, when the handle is moved off the end of the arm 18, but which under normal conditions are folded alongside the arm and concealed within the hollow handle, as indicated in Fig. 3. Besides these 120 125 130

methods of indicating a broken wire, appealing to the senses of touch and sight, I may and preferably do, employ audible signals or alarms, such as an electric bell 37, which 5 may be located in a distant part of the ship, and also a mechanically operated bell 30, located at the instrument E. The circuit of the electric bell 37 is closed by the arm 15 coming into engagement with a contact 33 10 as represented in Fig. 5. The mechanically operated bell 30 is acted upon by strikers 32 that are hung from the ends of arms supported upon a shaft carrying a small pinion that is rotated by means of a rack 31 connected with the rod 20, as represented in 15 Figs. 2 and 3.

It sometimes happens that the wires become too tight and I have provided means for indicating this condition which I will 20 now proceed to describe. It will be understood that when the wires are tightened the wheels or pulleys 7 and 8 will be turned against the action of the spring 14 and hence the parts of the apparatus will be 25 caused to assume the positions indicated in Fig. 6, in doing which the yoke slides along the arm 18 toward the shaft 11. The cross-bar 28 uniting the rods 26 is located at such place that the yoke 17 comes into engagement therewith when the tightened wires 30 begin to assume a dangerous or undesirable degree of tension, and as the yoke continues to move toward the shaft 11, the cross-bar 28, the rods 26, and the band 25, carried 35 thereby, are all moved along the arm 18, compressing the springs 27. As will be seen by reference to Fig. 3, the band 25 is so disposed with reference to the toggle levers 24 that when it is moved as just described, it 40 operates to move the latch 23 and trip the handle which will thereupon immediately, under the action of the spring 22, assume the position indicated in Fig. 5, when the attention of the pilot and others will be called 45 to the fact that the wires are too tight, the several signals, alarm or indicating devices already described, being brought into operation the same as when in the case of a broken wire except this, that the band 25 50 bearing the sign, "Wire broken" will be moved inward and carried out of sight within the casing, at the same time exposing a sign, "Wire too tight" that may be placed upon that portion of the arm 18 which the band normally encircles.

The wires 9 and 10 connect the pilot's instrument E with the engineer's instrument F in the usual manner, except that, as described, they are maintained under spring 60 tension. Referring now particularly to Figs. 9 and 10, which illustrate the engineer's telegraph instrument, 34 designates the casing thereof of which is provided as usual with a face 65 plate 39 over which move the pointer 42 for

indicating the orders transmitted by the pilot, and a pointer 44 showing the responses made to the orders transmitted. The latter pointer is shown as secured fast to the wheel or pulley 45 to which are connected the response wires 10 leading to the pilot's instrument E and which is moved by the automatic response mechanism, to be described. This pulley is mounted loosely upon the shaft 38 to which is secured the pointer 70 42. The wires 9 pass around and are secured to the wheel or pulley 40, likewise loosely mounted upon the shaft 38. The latter wheel, 40, is connected with the shaft 38 to give motion to the pointer 42, through 75 friction clutch mechanism which I will now proceed to describe. 47 indicates a hub or enlargement of the shaft 38 from which extend arms 43 that support a cam 41, the main portion of the peripheral edge of 80 which is concentric with the axis of the shaft. In the arms 43 are mounted a pair of bell crank or angular levers 53 53' that carry eccentric heads 50 50' that bear upon the inner face 64 of the rim of the wheel or pulley 90 40, being held in engagement therewith by a spring 51 connected with the levers 53 53'. It will be seen by reference to Fig. 9 that if the wheel 40 be turned, whether in one direction or the other, the friction-clutching 95 members will so grip the surface 64 of the wheel as to connect the latter with the shaft 38, so they will turn as one. It is through this friction clutch mechanism that the indicating hand or index 42 is operated 100 from the pilot's instrument. It sometimes occurs that one of the wires 9, from one cause or another, changes in length as compared with the other so that the movement of the indicator 42 is not in exact accord 105 with that of the handle 4 of the instrument E and the indicator carried thereby. The friction clutch mechanism described permits resetting of these two indicators so that they shall be in exact positional agreement whenever the pilot desires to change the signal. 110 It is customary for the pilot when a signal is to be changed to quickly throw the arm 18 of his instrument over as far as it will go in the direction of the signal to be given and then to bring it back to the position indicating the speed at which the engine is to be moved. When this is done the wheel 40 and the parts connected thereto through the friction clutch above described, are moved 115 120 until an arm, 52 or 52', of one of the levers, 53 or 53', comes into engagement with one of the adjustable stops, 35 or 35', carried by the casing 34. These stops are so adjusted that the contact between the parts 52 and 125 35 is just made when the pilot has turned the arm of his instrument to the extreme limit, provided the wire through which the instruments E and F are connected be under proper tension. If, however, the ten- 130

sion of the wire has for one reason or another, been changed so that the arm 52 comes into engagement with the stop 35 before the end of the movement of the arm of the pilot's instrument, the lever 53 will be sufficiently rocked in its bearing to throw the clutch 50 from engagement with the wheel, which then turns independently of the shaft 38 so long as the arm of the pilot's instrument continues to move in the direction in which it was moving when the parts 52 and 35 came into engagement. When the return movement of the arm begins the other friction clutch comes into operation and the parts it unites move together, with the index 42 traveling in synchronism with the pointer or index 3 of the other instrument. The pointers may thus at any time be set to agree with each other by a complete throw 20 of the arm 18 at the pilot's instrument from one limit of its movement to the other.

The wires as they enter the casing 34 and before they pass to the pulleys 40 and 45, engage with the pulleys 61 arranged to divert their course and also to serve as friction-reducing devices. As represented in Fig. 9, these pulleys are mounted in pivoted arms 158 which are connected by a spring 159 that tends to draw the pulleys 30 and their supporting arms toward each other. The tension of the wires, however, separates the pulleys and puts the spring under stress so long as the parts are in working position. Should a wire break, the spring draws the pulleys toward each other and the parts assume the position shown in the drawings. 160 designates a semaphore pivoted within the casing to one of the arms 158 and connected with the other arm by 40 a link 161. The semaphore is moved so as to extend out of the casing whenever the parts are in the position shown in full lines and indicates that a wire is broken. When in this position it may be used as a circuit 45 closer for an electric bell signal as shown. When the parts are in normal position with the wires under tension and the pulleys 61 separated, the semaphore is carried within the casing and concealed, as indicated in 50 dotted lines.

I will now describe the mechanism by which an improper response on the part of the engineer to the order given by the pilot is indicated.

55 48 indicates a pipe containing steam or other fluid under pressure. Adjacent to the instrument F or F' the pipe is provided with a valve casing 63 in which is located a valve 49 having a stem 54 that passes out 60 through the casing, the valve being normally held to its seat by a spring 55. A rocking bar 60, in the form of a lever of the first order, is supported upon that end of the stem of the valve 49 that projects outside 65 of the casing 63. To provide for adjust-

ments which are found desirable I make the seat or bearing for the end of the valve stem adjustable. Thus, as shown, the end of the stem may rest in a recess formed therefor in a screw-threaded stem 58 that is mounted in a screw-threaded portion 59 of the lever 60. A locknut is employed to hold the stem in place after being properly adjusted. Two links, 62, 62', connected with the rocking lever 60 upon opposite sides of its fulcrum 70 unite it with levers 56, 56', suitably mounted within the casing 34, and carrying rollers or contact pieces 67, 67' that lie in the path of and are adapted to be engaged by the cam 41. These levers also carry other rollers or contacts, 57, 57', that lie in the path of and are adapted to be engaged by a peripheral cam 46 carried by the wheel, 45, with which the response wire, 10, is connected. These cams 41 and 46 are so disposed that 80 when the response parts of the telegraph are in accord with the signal-giving parts, then the cams lie one behind the other, with the result that both cams act simultaneously upon the two rollers carried by a single lever, the opposite lever, whichever that be, then occupying the position indicated in dotted lines in Fig. 9. In this view the parts are represented in full lines as being in the positions which they would assume had the 90 order received from the pilot been improperly executed; the drawing showing that the signal given was half speed astern, and the response movement of the engine half speed ahead. Under these conditions both levers, 100 56 and 56', are moved outward by the cams 41, 46, with the result that the links, 62 and 62', are both moved toward the left and the valve 49 is unseated, as indicated. But should the engineer have properly executed 105 the order given, the position of the cam 41 would be that illustrated, while the cam 46 carried by the response wheel would be directly behind the cam 41. Then the lever 56' would occupy the position indicated in 110 full lines in the drawing and the lever 56 the position indicated by dotted lines, and this would result in tilting the lever 60, its upper end being inclined toward the right (see Fig. 19) but the valve would not be 115 moved from its seat. The other movements of these parts will be apparent without further description.

The lever 60 may be arranged to operate an alarm when moved to position to open 120 the valve 49, and I have, in Fig. 10, illustrated a circuit closer which may constitute a part of an electric circuit including an alarm of some sort that is closed when the lever is moved to open the valve.

125 The cams 41 and 46 are so proportioned and related that when turned to the positions indicated in dotted lines in Fig. 9—the positions they assume when the pilot turns the arm 18 of his instrument to the "through" 130

with signal" position, indicating for instance that he has left the pilot house and is using a bell pull instrument located at another part of the ship—the levers 56, 56' 5 both assume the positions indicated by dotted lines, since the contact rollers which they carry are then between the cams. When thus arranged the movements of the engine will not operate the safety devices connected 10 with the engineer's instrument F. This arrangement is of advantage because it frequently happens that the engineer desires to operate his engine, as for instance, in warming up before leaving port, and before 15 the pilot or captain has assumed his post, and under these circumstances it is not desired that the alarm and safety devices described should operate.

In Figs. 11 and 12 I have illustrated an engineer's telegraph instrument, embodying some features of my invention, that is in most respects similar to that indicated in Figs. 9 and 10, but differs in that the pipe 48 is provided with two valves instead of one, and has the mechanism for operating these valves modified accordingly. Similar letters of reference are applied to like parts in both sets of views, the exponent prime being in some instances applied in Figs. 11 and 12 where parts similar in function to those shown in Figs. 9 and 10, are structurally different or are differently arranged, and therefore a detail description of this embodiment of my invention does not seem to be necessary. It is apparent that when an order is properly executed and the two cams, 41' and 46, lie one behind the other, but one of the valves in the pipe 48 can be opened at a given instant of time, and hence the pipe 48 is obstructed and fluid can not pass through it. On the other hand, should an order be improperly executed, the cams assume the position indicated in dotted lines in Fig. 11 and both valves are simultaneously opened.

The reason for opening the valve or valves in the pipe 48 when the engine does not move in proper response to the order transmitted, is that a signal, or warning, or indication of some sort, showing that a mistake has been made shall be given, or that the engine shall be automatically stopped, or that both signaling and stopping operations shall take place.

55 For an illustration of the parts now to be described, Figs. 1 and 13 should be consulted.

G represents a whistle connected with the pipe 48 and adapted to sound and give an audible warning immediately upon the valve or valves in pipe 48 being opened. This pipe is also connected with the motor H that serves to automatically stop the engine. This motor is represented as being a simple cylinder in which moves a piston that is connect-

ed, through the link h or other connection, with the main throttle valve b . The passage of fluid from the pipe 48 into the cylinder of the motor H is governed by a valve 100, that in turn is controlled by the delay mechanism I, which as has been described, is arranged to be operated from the main engine through connections i . As illustrated, one element of this connecting mechanism is a reciprocating rod adjustably connected with a vibrating lever 70 through the yoke 71 so that the amplitude of the vibrations imparted to the lever 70 may be varied as may be desired. Within the casing of the delay mechanism I, which casing is not shown at all in Fig. 13, is mounted a set of wheels concentrically supported upon a shaft that constitutes the axis about which the lever 70 vibrates. The wheels are a ratchet wheel 74, a belt pulley 104, and a ratchet wheel 75. Operating pawls 72 and 73 engage respectively with the ratchet wheels 74 and 75, these pawls being carried by extensions of the lever 70 and connected with each other so that they engage with or are separated from their respective ratchets simultaneously. With the ratchets of the said wheels 74 and 75 there also engage the locking dogs 76 and 77, which likewise are connected so as to be moved simultaneously. The ratchet wheel 75 is secured fast to the belt pulley 104 so that they turn together, and the ratchet of this wheel is broken, leaving an untoothed section or sections with which the pawl 73 at times comes into engagement. The belt wheel is connected, through chains or other suitable train of gearing, indicated generally by 103, with the lock e of the throttle lever. 69 is a lever arranged to engage with the tail ends of the pawl 72 and dog 76 and throw them and also the connected parts 73 and 77, off from the ratchets with which they respectively engage. A spring 105 tends to hold the lever 69 in engagement with the pawls 72 and 76. A piston 68, arranged within a cylinder 66, is connected with the lever 69, and the interior of the cylinder, back of the piston, has free connection with the pipe 48'. In the wheel 74 are formed a series of holes into any one of which may be set a pin 79 that is adapted to engage with the forked end of a rocking lever 102, that is connected, through a link 101, with the valve 100 controlling the flow of fluid from the pipe 48' to the motor H. 78 indicates an adjustable plate secured to the wheel 74 and adapted to engage with a pin 98 carried by the operating pawl 72, in order to throw out of engagement the operating pawls whenever the wheel has been turned the desired extent. The operation of this part of the apparatus is as follows:

Supposing the engine has been started in a direction opposite to that for which the order was given, and the valve 49 has been 130

opened in the manner already described. Steam or other fluid under pressure is thereupon admitted to the pipe 48' beyond the valve and at once sounds the whistle G. At 5 the same time, the piston 68 within the cylinder 66 is forced outward by the motor fluid from the pipe 48' and moves the lever 69 against the action of the spring 105, releasing both the operating pawls and the locking dogs. 10 Thereupon the vibrating lever 70, which is in constant motion whenever the engine is moving, turns the wheels 74 and 75. The wheels 75 through the belt pulley 104 and the train of mechanism 103, unlocks 15 the throttle lever b. After the desired number of revolutions of the engine, for which the delay mechanism may have been set have taken place, the pin 79 engages with the lever 102 and opens the valve 100, the parts 20 being so adjusted that the throttle lever is unlocked a little before the valve is opened. Upon the valve being opened fluid is admitted to the cylinder of the motor H, which at once moves the lever b to close the 25 main throttle of the engine and thereby automatically stop it. For reasons that are understood by marine engineers, it is desirable that the engine should not be instantaneously stopped should it be started in a direction contrary to the order given, but rather that there should be a short delay in stopping, variable according to the type of engine being controlled, whether high speed or slow-moving. It is for these latter 30 reasons that the pin 79 is adjustable. The hole in which the pin is inserted determines the number of reciprocations of the operating parts that shall take place before the valve 35 100 shall be opened and the engine stopped. 40 There may be two or three reciprocations only or one hundred or more according to the position to which the pin is set, which in turn is governed by the type of engine with which this apparatus is used.

45 The adjustable plate 78 for throwing out of action the operating pawls, is used for the purpose of preventing the mechanism being turned to an extent to injure the parts under any circumstances or contingencies of operation. It will be understood that under 50 normal conditions, that is, when the engine is being caused to operate in proper response to orders transmitted, there is no pressure upon the pipe 48' nor within the cylinder 66, and hence, the lever 69 is held by the spring 55 105 in position to throw the operating pawls and the holding dogs out of engagement with the ratchet wheels with which they respectively engage, which wheels thereupon, 60 being free, return to normal positions under the influence of the spring 214.

I will now describe the mechanism by which the response parts of the system are automatically controlled and operated from 65 the movements of the engine itself, which

mechanism is also employed to operate the indicating apparatus that may be located in various parts of the ship for showing the direction and speed of movement of the engine, and in this connection refer particularly to Figs. 1, 14, 15 and 16.

115 designates a pulley with which are connected two wires L L through which the movements of the engine are communicated to the response-indicating devices. This 75 wheel 115 is preferably made up of two parts 7 and 8 connected by a coiled spring 14 in order that the wires L may be maintained under proper tension in the manner already hereinbefore set forth. The wheel 115 is 80 connected through mechanism later to be described, with a pulley 113 that is belted to or otherwise connected with the way-shaft c, the pulley being turned to one position when the way-shaft is set for moving the engine 85 forward, and to another position when set to turn the engine backward. The hub 117 of the pulley surrounds the end of a shaft 112 that is hollow and constitutes a conduit for air or other fluid. The conduit 112 is 90 connected with a pump or compressor N that is operated whenever the engine is in motion, being connected therewith as indicated at n in Fig. 1. The intake pipe m of the pump preferably opens outboard so 95 as to take in air at normal atmospheric temperature. The pipe 112 is stationary and is formed with a port 116 adapted to communicate with one or the other of the conduits 119 120 carried by the pulley 113, according- 100 105 110 115 120 125 130 135 140 vention is as follows: The way-shaft having been turned to start the engine, in one direction or the other, moves the pulley 113, and in so doing puts one of the cylinders, 5 121 or 122, into communication with the conduit 112, and through this with the pump or compressor N. As soon as the engine starts to move, the compressor is operated and it works with a speed and power proportionate to the speed of the engine, pumping relatively little when the engine moves slowly, and relatively much when it is moving at full speed. The fluid from the compressor is delivered to the cylinder with 10 which it has been put into communication and moves the piston therein. At the same time the indicator K is operated by fluid conducted through the conduits M. As the engine moves slowly the piston rod 126 will 15 be moved to uncover the first of the ports 128, which will be ample to serve as a vent or exhaust for the pump while moving very slowly; but as the speed increases, the pressure within the cylinder back of the piston 20 will increase proportionately, and the piston is moved farther outward, against the action of the spring 127, until the second of the series of the ports 128 is uncovered. 25 And thus the movement of the piston responds to the pressure in the cylinder in which it works, and this pressure corresponds with the speed of the engine. The final port of the series is unrestricted by a 30 valve and is of a size to permit the exhaust 35 of the fluid from the compressor when run at the highest speed for which the engine is designed.

The automatic response-controlling mechanism J is connected with and operates those 40 response parts of the ship's telegraph which are commonly manually operated by the engineer after he has received an order from the pilot, for the purpose of indicating that the order has been received and is understood. In Fig. 1 the wires L L are represented as being connected to the pulley 115, and with the response wires 10 of the ship's telegraph. They are also connected with an indicator K' having a pointer 133, and 45 with the index or pointer 144 of the engineer's instrument, F'.

147 indicates an arm extending from the piston rod 126 and connected by a link 148 with an arm 149 that is preferably 50 mounted so as to turn about the same axis as do the wheels 113 and 115. A portion of the arm is preferably formed into a hollow cylinder 150 upon which is mounted a sliding clutch ring 152. The clutch ring 152 corresponds in operation and function with 55 the sliding yoke 17 illustrated in Figs. 2, 3 and 4, and the arm 149, 150, with the arm 18 of the said views. The clutch ring is connected upon one side of the arm 150 with 60 the part 7 of wheel 115, by means of the 65

link 19, and upon the other side of the arm it is connected by the link 16 with an arm 15 which is united with the section 8 of the said wheel. These parts last described are the same in construction and operation as 70 the correspondingly designated parts that have already been described, and which are illustrated in Figs. 2, 3, and 4. It will be understood without further description, that whenever the pulley 113 is turned, the arm, 75 149, 150, will be correspondingly rotated, the wheel 115 turned, and the response-indicating devices, wherever they may be situated, operated. The direction of movement of the engine is thus indicated. The speed 80 of movement will be indicated by further movements of the indicating devices communicated through the parts described, imparted by the longitudinal movements of piston rod 126 in its supporting cylinders. 85

The clutch ring 152 is utilized as a means for controlling the operation of the indicating devices that show unusual tension conditions of the wires L L. Should one of these break, the ring will be forced outward by reasons of the relative movements 90 of the two parts, 7 and 8, of the wheel 115, in the manner already set forth in describing Fig. 5, and in thus moving will engage with the outer end of a lever 153 pivoted 95 within the portion 150 of the indicating arm and extending out through openings therein on either side of its fulcrum. This lever is connected by a link 154 with the operating lever of a valve located within the casing 100 155 which controls the passage of steam or other motor fluid to a whistle or other alarm device 156. The pipe through which steam or other fluid for sounding the alarm is delivered to the valve casing 155 is designated 105 157 and preferably serves as one of the supports for the control mechanism J.

In certain types of engines, such as steam turbines and gas engines, a way-shaft is not employed, and to adapt the control mechanism J to such engines, connections such as indicated in Fig. 18 may be employed. In this view 134 designates a rotating shaft turning in one direction when the engine moves forward and in the opposite direction when it is reversed. Upon this shaft is situated a band 136 in which is formed a recess 137. With this recess there engages one or the other of a pair of pawls 138 mounted in a suitable supporting head 120 which is carried by a bar 139 that is mounted so as to be free to slide in a rocking block 140. A spring 142 holds the arm against the shaft with one or the other of the pawls in position to engage with the 125 notch or recess 137. 143 designates other springs connected with the rod 139 and holding it in working position. With this rod is connected a link 146 that is adapted to be connected with the wheel 113 of the 130

control apparatus J and which in function corresponds with the band or belt *j*, Fig. 1. When the shaft is turning in one direction, as for instance that indicated by the arrow in Fig. 18, the parts are carried to the position indicated in full lines, and the rod or link 146, being pulled down, will shift the pulley 113 to one position. Upon the shaft being turned in the reverse direction, the lower pawl is engaged by the upper edge 10 of the recess 137 and the parts turned to the position indicated in dotted lines, whereupon the connecting rod 146 will be carried upward and the pulley 113 connected therewith shifted to a different position.

Many of the improvements which I have already described in connection with a ship's telegraph having the pilot's and the engineer's instruments E and F may be embodied in a ship's signaling apparatus of the bell pull type, and I have in Figs. 19 to 22 illustrated the invention applied to apparatus of this kind. In designating the parts represented in these views I have employed 20 similar reference characters to those used in Figs. 9 and 10 where the parts are identically similar to those employed in the ship's telegraph apparatus, and where the parts are different in construction but analogous 25 in function I have employed reference characters one hundred higher in number than those used in Figs. 9 and 10.

Referring to Figs. 19 to 22, 109 designates the wires to which the bell pulls, 165, 166, 30 are connected and which lead to the engine room for the purpose of ringing the signal bell or bells therein. 110 designates the wire connected with the wire L of the automatic response-indicating mechanism. In 35 Figs. 21 and 22 I have indicated two sets of wires 109, one set coming from one part of the vessel and another from another part, and both connected and arranged so that the signals are given upon the same bell or 40 set of bells.

All of these wires are maintained under 45 spring tension. Thus the wires 109 are connected with pulleys or drums 7 and 8 shaped to form a shell in which is mounted the coiled tension spring 14. The pulley 145 with which is connected the signal wire 110 is maintained under tension by the spring 114. The response wheel 145, connected to the operating mechanism J through a wire 50 L, has secured to it an index pointer 144 that travels past a sight opening in the casing of the instrument, indicated by dotted lines in Fig. 19. The friction clutch mechanism by which the differences in the length 55 of a wire may be compensated for and taken care of consist (see Figs. 27, 28 and 29) of rods 164, to which the wires 109 are attached, and clutch plates 150 150' held apart by springs 151, so that one or the other 60 clutch frictionally grips a rod whenever it

is moved. The clutch throw-off devices consist of the stops 135, 135', the latter being preferably adjustable.

The following mechanism is employed to indicate when an improper movement of the engine occurs in response to an order transmitted to the engineer.

48 is a steam pipe provided with a valve situated in the casing 63, the stem of the valve 54 extending out through the casing 70 and having supported upon it the rocking lever 60. 162 162' indicate links connected with the rocking lever 60 upon opposite sides of its fulcrum, and also connected respectively, either directly or through intermediate mechanism, with levers 167, 167' which in turn are acted upon by camming levers 141, 141. The levers 141 are connected together so as to move synchronously by a connecting bar 80 and are held in the 85 positions to which they may be set by a spring 81 connected with said bar. The camming levers 141 are operated by bars 82 which are conveniently carried by the rods 164. 146 indicates a cam movable with the 90 response-indicating devices, it being represented as supported by the pointer 144. It is arranged to operate levers 157, 157', connected respectively, either directly or through intermediate mechanism, with the 95 links 162, 162'. In Fig. 19 the parts of the apparatus are represented in the position occupied when an order to go ahead has been transmitted and properly executed, the wires 109 and the parts connected therewith being 100 pulled. This operation brings the end of the rod 82 into engagement with the camming lever 141 which is thereby moved from the position indicated in dotted lines to that shown in full lines, where it is held by the 105 spring 81 after the pull upon the wire 109 is released and the rods 164 and 82 returned to normal positions. In moving, the end of the camming lever engages with the contact lever 167 which is thereby rocked, and, 110 through its intermediate connections, moves the link 162 toward the right, tilting the lever 60 upon its fulcrum. This movement also tilts the lever 157 into such position that when the cam 146, moved by the response devices, comes to the position shown in full lines, it does not operatively engage with or move the lever, and hence, the response to the order given being properly executed, no alarm or other movement to attract attention is given. Should, however, the order be improperly executed, the cam 115 would be moved toward the right and into the position indicated by the dotted lines in Fig. 19, and in coming into this position it 120 would act upon the lever 157' rocking it and, through its intermediate connections, moving the link 162' toward the right, resulting in opening the valve within the casing, in the manner indicated in Fig. 9.

The levers 167, 167' are preferably connected by a spring 83, that operates to move these levers into position to be engaged by the camming levers 141. As these levers 167, 167' are connected, through the links 162, 162', with the rocking lever 60, the spring 83 also operates to normally hold the valve within the casing 63 closed.

84 indicates the signal gong and 85 the 10 single stroke hammer for operating thereon, connected with one of the wires 109. The jingle striker is designated 86 and is arranged also to operate upon the gong 84, and is connected, as indicated, to be operated 15 by the other wire 109.

When two sets of signal wires come to the instrument as indicated in Figs. 21 and 22, they may both be arranged to ring the same gong 84. Should one of the wires 109 or 110, 20 become broken, I provide devices for indicating this fact. In Fig. 19 I have represented a flag or semaphore 125, bearing the words "Wire broken," mounted within the case of the instrument F' adjacent the sight 25 opening. This semaphore is connected by links 87 and 88 with levers 89 and 90 arranged to be engaged and operated by stops 91, 91 secured, respectively to the rods 164. A stop 92 carried by the wheel 145 is arranged 30 to engage with the arm 93 of the lever 90 whenever the wire 110 is broken. A pivoted semaphore 94 bearing the words "Ahead" and "Astern" is connected through suitable mechanism 95 with the camming 35 levers 141, and is arranged to display at the sight opening the word designating the direction in which the engine is to be turned.

An electric indicating mechanism such as indicated at 96, Fig. 21, may be employed to 40 indicate abnormal conditions of the wire.

As the breaking of one wire does not interfere with the operation of the other, I provide means by which the tone of the bell may be modified should one of the wires be 45 broken and thereafter a signal transmitted by or through the other wires. Thus as indicated, the signal or signals which indicate a broken wire are arranged to operate a damper 97 for the gong 84 which is brought 50 into engagement therewith and there held until the normal conditions are restored.

As represented in Figs. 23 and 26, the bell pulls 165, 166, are constructed so as to be operative so long as the tension upon the 55 wires 109 is properly maintained, but become inoperative should the wires break or become unduly slackened. As represented in the drawings, the wire is connected with a plunger 170 that is so constructed that it 60 will lock the hand piece, 165' or 166' of the bell pull so long as it occupies the position shown in full lines, and this position will be maintained so long as the proper tension is upon the wire 109. A spring 171, of less 65 force than the spring that maintains the

wire under tension, is arranged within the casing 172 in which is situated the plunger, and bears against the latter, tending to release the hand piece, as indicated by dotted lines in Fig. 23. It will be understood that whenever the wire 109 is slackened, through 70 breakage or otherwise, the spring 171 will lift the plunger and release the pivoted hand piece which will immediately become inoperative and will thus give notice to the 75 pilot that the wire with which it is connected is out of order. The plunger when released and forced upward by the spring 171 may be employed to close the circuit of an electric alarm 173, as indicated in Figs. 80 23 and 25.

What I claim is:—

1. The combination of a pair of instruments for sending and receiving ship's orders, two wires connecting the said instruments, a spring device for maintaining both the wires under a desired degree of tension, and alarm devices for indicating should the tension upon either wire become abnormal.

2. A pair of instruments for sending and receiving ship's orders, two wires connecting the said instruments, a pair of pulleys at one of the instruments with which the wires are respectively connected, a spring for 90 maintaining the wires under tension, connected with the said pulleys and arranged to turn them in opposite directions, and alarm devices connected with both of the 95 said pulleys and arranged to be operated by 100 the movements thereof should either wire become too tight or too loose.

3. The combination of two instruments for sending and receiving ship's orders, one of them being provided with a radially disposed swinging arm, two wires connecting the said instruments, a pair of pulleys at the instrument having the said radial arm to which the wires are respectively connected, a spring connected with the said pulleys for 105 maintaining the wires under tension, and connections between each of the said pulleys and the said radial arm whereby they are 110 caused to turn together.

4. The combination of two instruments 115 for sending and receiving ship's orders, one of them being provided with a radially disposed rotatable arm, two wires connecting the said instruments, a pair of pulleys at the instrument having the said radial arm, to which the wires are respectively connected, a spring connected with the pulleys for 120 maintaining the wires under tension, and connections between each of the said pulleys and the said radial arm whereby they are caused to turn together, the said connections being 125 movable along the arm thereby permitting one pulley to turn with reference to the other.

5. The combination of two instruments 130

- for sending and receiving ship's orders, one of them being provided with a radially disposed rotatable arm, two wires connecting the said instruments, a pair of pulleys to which the wires are respectively connected located at the instrument having the said arm, and supported so as to turn about the same axis as that about which the arm moves, a spring connecting the said pulleys for maintaining the wires under tension, and a pair of links having sliding connections at their inner ends with the said radial arm and being connected on opposite sides of the arm and at their outer ends with the said pulleys.
6. The combination of two instruments for sending and receiving ship's orders, one of them being provided with a radially disposed freely movable rotatable arm, two wires connecting the said instruments, a pair of pulleys to which the wires are respectively connected located at the instrument having the said arm, a spring connected with the pulleys for maintaining the wires under tension, a pair of links having sliding connections at their inner ends with the said arms and at their outer ends, upon opposite sides of the arms, to the said pulleys whereby when uniform tension is maintained upon the wires the pulleys and the arm turn together, but when one of the wires is subject to abnormal conditions the arm and pulleys turn relative to each other, and alarm devices operated by the sliding connection of the said links with the arm when the parts are moved incident to abnormal tension conditions of the wires.
7. In a ship's telegraph, the combination of a pilot's sending instrument, provided with an arm free to be turned to transmit orders, a pair of wires leading from the pilot's instrument to the other instrument of the telegraph, a handle to be grasped, applied to the said swinging arm, and means for disengaging the said handle from the arm whenever one of the wires becomes broken.
8. In a ship's telegraph, the combination of a pilot's sending instrument, provided with an arm free to be turned to transmit orders, a pair of wires leading from the pilot's instrument to the other instrument of the telegraph, means for maintaining the said wires under tension, a handle to be grasped, applied to the said swinging arm, and means for disengaging the said handle from the arm whenever the tension upon a wire becomes abnormal.
9. In a ship's telegraph, the combination of a pilot's instrument provided with an arm free to be turned to transmit orders, a pair of wires leading from the pilot's to the other instrument of the telegraph, a pair of pulleys to which the wires are respectively connected, a spring connected with the said pulleys for maintaining the wires under tension, a loose handle applied to the said movable arm to be grasped in sending orders, means for holding the handle in place under normal tension conditions of the wires, and means connected with the said pulleys for releasing the handle when the tension conditions of either wire are abnormal.
10. In a ship's telegraph, the combination of a pilot's instrument provided with an arm free to be turned to transmit orders, a handle loosely applied to the end of the arm, a catch for holding the handle in place upon the arm, a trip for operating the catch to release the handle, wires leading from the pilot's to the other instrument of the telegraph, means for maintaining the wires under proper tension, and means connected with the wires arranged to operate the trip and release the handle when the tension conditions of either wire become abnormal.
11. In a ship's telegraph, the combination of a pilot's instrument provided with an arm free to be turned to transmit orders, a handle loosely applied to the end of the arm, a catch for holding the handle in place upon the arm, a trip for operating the catch to release the handle, wires leading from the pilot's to the other instrument of the telegraph, means for maintaining the wires under proper tension, means connected with the wires arranged to operate the trip and release the handle when the tension conditions of either wire become abnormal, and indicating devices operated when the handle is released.
12. In a ship's telegraph, the combination of a pilot's instrument provided with an arm free to be turned to transmit orders, a handle loosely applied to the end of the arm, a catch for holding the handle in place upon the arm, a trip for operating the catch to release the handle, wires leading from the pilot's to the other instrument of the telegraph, a pair of pulleys to which the wires are respectively connected, a spring for engaging the pulleys and maintaining the wires under tension, a yoke encircling the said movable arm and movable along the same, links connected at their inner ends with the yoke and at their outer ends connected respectively with the said pulleys on opposite sides of the arm, and means operated by the said yoke for tripping the catch that holds the handle when either wire is under abnormal tension conditions.
13. The combination with a pilot's and an engineer's instrument for sending and receiving ship's orders, and wires connecting the said instruments,—the pilot's instrument being provided with means that are moved when orders are transmitted, and the engineer's instrument with means that are moved to designate the orders given,—of lost motion connections interposed be-

tween the said moving parts of the two instruments and means arranged to automatically break the said connections between the two instruments whenever the moving part of the receiving instrument reaches its limit of movement before the moving part of the sending instrument reaches its corresponding limit of movement, whereby the said moving parts may be set to move in proper accord with each other through full movements of the order-transmitting parts of the pilot's instrument, substantially as set forth.

14. The combination of a pilot's and an engineer's instrument for sending and receiving ship's orders, the engineer's instrument being provided with order-indicating parts, wires connecting the said instruments, and friction clutch mechanism interposed between the said wires and the order-indicating parts of the engineer's instrument arranged to normally connect said parts and also to permit one to move relative to the other under desired conditions.

15. In apparatus for transmitting ship's orders, the combination of a pilot's instrument, an engineer's instrument provided with movable parts for indicating the orders given, connections uniting the movable parts of the said instruments, friction clutch mechanism between the said connections and the order-indicating parts of the engineer's instrument, and stop devices for disengaging the said friction clutch mechanisms at the determined limits of movement of the order-indicating parts of the engineer's instrument.

16. In a ship's telegraph, the combination with a pilot's instrument having a movable arm that is turned in giving orders, an engineer's instrument provided with movable parts by which the orders transmitted are indicated, and wires connecting the said instruments, of friction clutch connections interposed between the said moving parts of the two instruments, and stop devices for throwing the said clutches out of action when the said moving parts of one of the connected instruments reaches the full limit of its movement before the other, thereby permitting the parts to be set at will in accord with each other, substantially as set forth.

17. In a ship's telegraph, the combination of a pilot's instrument, wires connecting it with the engineer's instrument, an engineer's instrument provided with a pulley with which the said wires are connected and an index pointer, these being free to turn relative to each other, frictional clutch devices uniting the said pulley and the pointer to cause them to normally move together, and adjustable stop devices for disengaging the friction clutch devices when

the index pointer reaches its respective limits of movement.

18. In a ship's telegraph, the combination of a pilot's instrument, wires connecting it with the engineer's instrument, an engineer's instrument provided with a pulley with which the said wires are connected and an index pointer, these being free to turn relative to each other, a pair of levers provided with friction contacts adapted to engage with the said pulley, springs for holding the levers in engagement with the pulley, a supporting frame in which the said levers are mounted connected with the index pointer, and stops with which the said levers are respectively adapted to engage when the index pointer reaches its extreme limits of movement, in order to separate the friction contacts of the levers from the pulley and free the latter from the pointer.

19. In apparatus for transmitting ship's orders, the combination of an engineer's instrument having movable parts for indicating the orders given, a cam moving therewith, alarm or signal devices, response devices for indicating the actual movements of the engine, and a cam device operated by the said response devices and co-operating with the cam device of the order-indicating parts, to actuate the alarm or signal devices whenever the movements of the engine are contrary to the order transmitted.

20. In a ship's telegraph, the combination of an engineer's instrument having a pulley with which connect the wires coming from the pilot's instrument and a movable response wheel turning on the same shaft as does the said pulley, a cam movable with the said pulley, another cam movable with the response wheel, an alarm and means for operating the alarm arranged to be acted upon by each of the said cams and being arranged to act only when the response wheel shows that an order has been improperly executed.

21. The combination of an engineer's instrument of a ship's order apparatus, a pressure fluid pipe, means for controlling the flow of fluid through the said pipe, safety devices operated by the flow of the fluid through the pipe, response devices for indicating the actual movements of the engine, and means controlled by the said response devices arranged to operate the devices that permit the flow of fluid through the said pipe whenever the movements of the engine are contrary to the order transmitted, substantially as set forth.

22. The combination of an engineer's instrument of a ship's order apparatus, means for shutting off the supply of power to the main engine, response devices, and means controlled by the response devices arranged

to operate the engine stopping devices whenever the movements of the engine are contrary to the orders transmitted.

23. The combination of an engineer's instrument of a ship's order apparatus, a fluid pressure pipe, valve devices for controlling the flow of fluid through the pipe, a motor for shutting off the supply of power to the main engine, response devices for indicating the actual movements of the engine, and means controlled by the said response devices arranged to operate the said valve devices to admit fluid from the said pipe to the motor whenever the movements of the engine are contrary to the order transmitted.

24. The combination of a main ship's engine, means for controlling the supply of power for operating the engine, a motor for shutting off the said power, delay mechanism operated from the main engine for controlling the operation of the said motor, an engineer's instrument of a ship's order-transmitting and receiving system, and movable response mechanism for indicating the actual movements of the engine arranged to set into operation the said delay mechanism whenever the movement of the engine is contrary to the order given.

25. The combination of a main ship's engine, means for controlling the supply of power for operating the engine, a motor for shutting off the said power, delay mechanism operated from the main engine for con-

trolling the operation of the said motor, an engineer's instrument of a ship's order-transmitting and receiving system, movable response mechanism for indicating the actual movements of the engine arranged to set into operation the said delay mechanism whenever the movement of the engine is contrary to the order given, and adjustable means for controlling the relative length of time the delay mechanism shall operate before it permits the said motor to act.

26. In ship's order sending and receiving apparatus, the combination of a pilot's sending instrument having a hand piece that is grasped when an order is transmitted, a receiving instrument, means connecting the instruments, and means for putting the hand piece of the pilot's instrument into abnormal condition whenever the connections between the sending and receiving instruments are disarranged.

27. In apparatus for transmitting ship's orders, the combination of a pilot's instrument, an engineer's instrument, response devices indicating the actual movements of the engine, and means controlled by the response devices for stopping the engine whenever the movements thereof are contrary to the order transmitted.
